UNITED STATES PATENT OFFICE.

EDWARD KLEINHAMPLE, OF MILLVALE, PENNSYLVANIA.

SAFETY FEEDER FOR WRINGERS.

Application filed September 15, 1924. Serial No. 737,881.

To all whom it may concern:

Be it known that I, EDWARD KLEINHAMPLE, a citizen of the United States, residing at Millvale, in the county of Allegheny and 5 State of Pennsylvania, have invented new and useful Improvements in Safety Feeders for Wringers, of which the following is a specification.

This invention relates to feeding devices 10 for wringers, and more particularly to what I term a safety feeder for wringers.

One of the main objects of the invention is to provide simple and efficient means which may be readily applied to wringers of 15 standard construction such as commonly used in connection with washing machines whereby the articles to be passed through the rollers of the wringer can be fed thereto in such manner as to eliminate possibility 20 of the operator's fingers being drawn between the wringer rollers. A further object is to provide a device of the character stated which can be readily produced and applied at small cost and which will act as a supporting board or plate for facilitating feeding of articles between the wringer rollers. 25 Further objects will appear from the detailed description.

In the drawings:

30 Figure 1 is a front view of the feeder as applied to a wringer of standard construction;

Figure 2 is an end view;

35 Figure 3 is a section taken substantially on line 3—3 of Fig. 1.

The wringer A may be of any suitable or preferred construction, that illustrated being of a well known type and including two rollers B the upper one of which is 40 pressed toward the lower roller and is adjustable toward and away from the same in a known manner. These rollers may be rotated by hand or may be driven from a suitable source of power by means of a shaft C 45 which is operatively connected to the rollers by suitable gearing positioned in a casing or housing D. This wringer is intended to be mounted upon a motor-operated washing machine in a known manner and in position 50 to receive articles removed from the machine to be passed between the rollers B. Wringers of this type and the manner of mounting the same on washing machines are well known in this art and need not be further described in detail.

In carrying out my invention I provide a

supporting and brace strip 1 which is secured to the wringer frame in parallelism with and adjacent to the lower portion of lower roller B. Two brackets 2 are mounted on this strip and are removably secured thereon by means of securing screws 3. The body 2^a of bracket 2 is slotted from its lower end to receive strip 1 and screw 3 passes through arm 4 of the body and is threaded into arm 5. The arms 4 and 5 and screw 3 cooperate to provide clamping means whereby the brackets are removably secured on the strip adjacent to the ends thereof. A stub-shaft 6 is rockably mounted through outwardly projecting arm 2^b of bracket 2 and the outer portion of this shaft is bent to provide an integral crank 6^a. A stub-shaft 7 is rockably mounted through arm 2^b of the other bracket 2 and a collar 8 is secured on each of the stub-shafts, this collar being positioned adjacent to the inner face of arm 2^b. Collar 8 is provided with a tangentially extending finger 9. A sheet metal feed plate 10 is secured by rivets 11, or in any other suitable or preferred manner, to fingers 9, and the lower portion of this plate is extended about collars 8 and secured thereto by rivets 12, these rivets also serving to secure the collars on the stub-shafts. This provides plate 10 with an integral tubular portion 10^a which connects the collars 8 and serves to materially reinforce the plate. At its upper edge plate 10 is provided with a toothed or serrated portion 13 the serrations of which are rounded so as not to present any sharp points or corners such as would tend to puncture or tear the fabric of articles fed between the rollers B by the plate.

In using the device plate 10 is rocked upwardly and outwardly away from rollers B into substantially vertical position so as to permit an article which is passed between the rollers B to be readily placed upon the serrated portion of the plate, after which the plate is turned inwardly into the position illustrated thus so positioning the article as to ensure its being fed between the rollers during rotation of the same, as in Fig. 2. When the article is placed upon the serrated edge portion of the plate and the plate is turned into operative position, a portion of the article may be positioned beneath the plate but this portion will be withdrawn from beneath the plate by the action of the rollers, after which the article

will be fed between the rollers as indicated in Fig. 2. As the plate 10 can be quickly and easily turned into and out of operative position by means of crank 6^a, this provides 5 a very simple and highly efficient device which may be readily applied to a wringer of standard construction and by means of which all necessity of the operator's fingers being positioned at all closely to the rollers 10 of the wringer is eliminated thus effectually eliminating all possibility of the operator's fingers being drawn between the rollers and crushed or otherwise injured thereby, such as not infrequently occurs where 15 the articles are fed between the rollers directly by hand. This device can be readily produced and sold at small cost and can be readily applied to wringers of standard construction which is a very material advantage. 20

As will be noted more clearly from Figures 1 and 3, body 2^a of bracket 2 is somewhat thickened relative to arm 2^b and the upper end of the body is positioned slightly 25 below the upper edge of the arm thus providing a shoulder which acts as a stop element to limit movement of plate 10 toward the lower roller B thus supporting the plate at an inclination. When the plate is 30 in operative position it is disposed at an upward and inward inclination to the rollers and provides a continuous smooth surface over which the articles to be passed between the rollers can be readily drawn thus 35 facilitating feeding of the articles between the rollers. In this respect the smooth rounded surface presented by portion 10^a of the plate is of material assistance in facilitating drawing of the articles onto plate 40 10 and thence between the rollers.

What I claim is:—

1. An attachment for a wringer having compressing rollers, including supporting brackets, means for attaching the brackets 45 to the wringer below the lower roller thereof, a feed plate rotatably mounted at its outer edge between the brackets, and means for turning said plate about its axis of movement into and out of operative position, the plate when in operative position being disposed at an upward and inward inclination to the rollers with its free edge positioned between the rollers, said plate when in its inoperative position having its 50 free edge spaced away from the rollers and disposed for reception of articles placed thereon.

2. An attachment for a wringer having compressing rollers, including supporting 55 brackets, means for attaching the brackets to the wringer, a feed plate rotatably

mounted at its outer edge between the brackets, and means for turning said plate about its axis of movement into and out of operative 65 position, the plate when in operative position being disposed at an upward and inward inclination to the rollers with its free edge positioned between the rollers, said plate when in its inoperative position having its free edge spaced away from the 70 rollers and disposed for reception of articles placed thereon.

3. An attachment for a wringer having compressing rollers, including supporting brackets, means for attaching the brackets to the wringer, a feed plate provided at its outer edge with a rounded tubular portion rotatably mounted between the brackets, and means for turning said plate about its axis of movement into and out of operative 75 position, the plate when in operative position being disposed at an upward and inward inclination to the rollers with its free edge positioned between the rollers, said plate when in its inoperative position having its free edge spaced away from the 80 rollers and disposed for reception of articles placed thereon.

4. An attachment for a wringer having compressing rollers, including supporting 85 brackets, means for attaching the brackets to the wringer, a feed plate provided at its outer edge with a rounded tubular portion, collars secured in the ends of said tubular portion, and stub-shafts secured in said collars and rotatably mounted in the brackets, the plate being turnable about the axis of the shafts into and out of operative position, said plate when in operative position being inclined upwardly and inwardly of the rollers with its free edge between the same, the plate when in inoperative position being disposed to receive articles placed on the free edge thereof. 90

5. An attachment for a wringer having compressing rollers, including supporting brackets, means for attaching the brackets to the wringer, a smooth and flat feed plate rotatably mounted at its outer edge between the brackets for moving the free edge 95 of the plate toward and away from the rollers in accordance with turning of the plate about its axis of movement, the plate when in operative position being disposed at an upward and inward inclination to the 100 wringer rollers with its free edge positioned between the same, said plate when in inoperative position being disposed for reception of articles placed on its free edge. 105

In testimony whereof I affix my signature. 110

EDWARD KLEINHAMPLE.
